APPARATUS FOR CONNECTING METAL COATING ROLLS WITH A DRIVING MECHANISM

Max E. Bills, Gary, Ind., assignor to United States Steel Corporation, a corporation of New Jersey

Application November 26, 1952, Serial No. 322,766

3 Claims. (Cl. 118—258)

1

The present invention relates generally to continuous metal coating apparatus of the type wherein metallic sheets or strip are passed through a tank containing a molten coating metal such as zinc or tin. The invention relates particularly to the elements of such apparatus used for rotating the coating rolls thereof.

The coating rolls used in conventional metal coating operations, such as continuous hot dip galvanizing, operate almost completely submerged in the molten spelter. These rolls are ordinarily driven by a driving mechanism, such as a reduction gear unit and motor, located outside of the tank and at a higher elevation than the rolls.

Prior to my invention, the driving force was transferred from the driving mechanism to the rolls by means of a set of metal gears. The gears, which were disposed on the shaft extensions of the coating rolls, were necessarily partly submerged in the molten spelter and partly exposed to atmosphere. The rotative action of the coating roll gears during operation of the galvanizing apparatus created a "paddle-wheel" effect on the molten spelter. The churning action of the gears in the spelter caused excessive amounts of molten zinc to be exposed to the atmosphere and become oxidized. Oxidation of the zinc resulted in the formation of an excessive amount of undesirable "dross" which floated on the upper surface of the spelter and had to be skimmed off at frequent intervals. This necessitated frequent additions of fresh spelter to replace that lost through oxidation. Thus, the agitation of the molten spelter by the gears directly caused delays in operation and consequently increased production costs.

It is, accordingly, an object of my invention to provide metal coating apparatus wherein the coating roll and driving mechanism are joined by means of a direct shaft connection whereby the roll is rotated within the coating medium with a minimum amount of agitation of the medium.

This and other objects will become more apparent after referring to the following specification and attached drawing, in which:

Figure 1 is a plan view showing the apparatus of my invention in use connecting the coating rolls of a galvanizing unit to a driving gear box;

Figure 2 is an end elevation partly in section of Figure 1;

Figure 3 is an enlarged detail view partly in section of the roll connection of my invention;

Figure 4 is a sectional view taken on the line IV—IV of Figure 3; and

2

Figure 5 is a sectional view of a modification of the apparatus of my invention.

Referring more particularly to the drawings, reference numeral 2 indicates a spelter tank of a continuous hot dip galvanizing line containing molten spelter X. A pair of coating rolls 4 are rotatably mounted in the tank in conventional manner submerged to approximately their axial centerlines. Driving means, which may consist of a motor 6, speed reduced 8 and gear box 10, may be disposed on a platform 12 adjacent the tank 2 at a slightly higher elevation than the rolls 4. The apparatus thus far described is conventional and is not claimed as my invention.

Reference numeral 14 indicates spindles which provide a direct shaft connection from gear unit 10 to each of the rolls 4. At one end 16, each of the spindles is inserted and locked in a sleeve 18 which in turn is pivotally connected with a drive shaft of the gear unit 10 by any suitable means such as a universal joint 20. The pivotal connection of the sleeve 18 permits limited movement of each of the spindles 14 in a vertical plane.

The end of each of the spindles 14 remote from the driving means is formed in the shape of a ball 22 having a transverse center hole 24 therethrough. A pin 26 having spherical ends 28 is inserted in the hole 24. As shown in Figure 4, the pin 26 is of sufficient length so that its ends project outwardly of the hole 24.

Each of the rolls 4 is provided with integral shaft or neck portions 30 and 32 projecting from the ends thereof. The shaft ends 32 are journaled in conventional bearings 34 supported in the tank 2. Each of the shaft ends 30 is provided with a counterbore 36 for the purpose of receiving the ball end 22 of the spindle 14 as will be more fully described hereinafter. The counterbores 36 may be each fitted with a split ring liner sleeve 38 made up of a pair of split ring sections 40. The sections 40 may be fastened in the counterbores by means of rivets or by welding so that their relative positions will not change after installation. The sections of each split liner are shaped to conform to the inner curvature of the counterbore and are spaced apart so that their opposed edges define a pair of opposed longitudinal slots 42 parallel

to the axis of the respective coating roll. The ball ends 22 are each dimensioned to fit snugly within the counterbores 36 with the projecting end of the pins 26 engaged in the slots 42. The pin 26 extends from both sides of the ball 22 a distance equal to the thickness of the split liner

50
55

38. The ends 28 of the pin are spherical to conform to the curvature of the counterbore with necessary clearance.

In assembly, the coating rolls are mounted in the tank 2 in conventional manner as best shown in Figures 1 and 2. The ball end 22 of each of the spindles 14 is slipped into the counterbore 26 of its respective roll so that the projecting ends of the pin 28 are engaged in the slots 42. The opposite end of each spindle is fitted into a sleeve 18 and the sleeve is connected with the gear box 16 in the manner described above. Since the coating rolls and the power delivering spindles are in substantially fixed positions longitudinally, it is unnecessary to provide any means to prevent the balls from coming out of the counterbores during operation.

In operation, there is a complete absence of any "paddle-wheel" effect during rotation of the coating rolls. The direct shaft connection between each of the coating rolls and the driving means results in a minimum amount of agitation of the molten spelter during operation.

Although I have found it preferable to insert a split sleeve lining in the counterbored ends of the roll shafts and a pair of opposed longitudinal slots defined by the edges of the split sections, it will be noted that the sleeve may be omitted entirely and slots 42 formed in the inner walls of the counterbores, as shown in Figure 5, or a solid sleeve may be used and the slots formed in the walls of the sleeve if desired. It will be noted further that the ball 22 may be formed with no transverse hole but with an integral pin or pins projecting from the surface of the ball if preferred. If one integral pin is used, only one longitudinal slot need be provided in the counterbores of the roll shafts.

While two embodiments of my invention have been shown and described, it will be apparent that other adaptations and modifications may be made without departing from the scope of the following claims.

I claim:

1. In a continuous metal coating apparatus including a tank for containing molten coating metal, a coating roll rotatably mounted in said tank, and driving means disposed adjacent said tank for rotating said roll, the improvement therewith of a flexible connection between said driving means and said roll, said flexible connection comprising a shaft projecting axially from one end of said roll, the outer end of said shaft

being counterbored, said shaft having a longitudinal slot in the inner side wall of its counterbore, a spindle pivotally attached at one end to said driving means, a ball on the opposite end of said spindle integral therewith, a pin projecting from the surface of said ball normal to the longitudinal axis of said spindle, said ball being fitted snugly in the counterbored end of said shaft with said pin fitted in said slot.

2. In a continuous metal coating apparatus including a tank for containing molten coating metal, a coating roll rotatably mounted in said tank, and driving means disposed adjacent said tank for rotating said roll, the improvement therewith of a flexible connection between said driving means and said roll, said flexible connection comprising a shaft projecting axially from one end of said roll, the outer end of said shaft being counterbored, a lining sleeve rigidly fitted in said counterbore, said sleeve having a longitudinal slot in the inner wall thereof, a spindle pivotally attached at one end to said driving means, the opposite end of said spindle being shaped in the form of a ball, a pin projecting from the surface of said ball normal to the longitudinal axis of said spindle, said ball being fitted in said sleeve with said pin fitted in said slot.

3. In a continuous metal coating apparatus including a tank for containing molten coating metal, a coating roll rotatably mounted in said tank, and driving means disposed adjacent said tank for rotating said roll, the improvement therewith of a flexible connection between said driving means and said roll, said flexible connection comprising a shaft projecting axially from one end of said roll, the outer end of said shaft being counterbored, a lining sleeve rigidly fitted in said counterbore, said sleeve consisting of a pair of split rings, the opposed ends of said rings defining a pair of opposed longitudinal slots, a spindle pivotally attached at one end to said driving means, the opposite end of said spindle being formed in the shape of a ball having a hole therethrough transverse to the longitudinal axis of said spindle, a pin inserted in said hole with its ends projecting outwardly therefrom, the ball end of said spindle being fitted snugly in said sleeve with the projecting ends of said pin fitted in said slots.
